UNITED STATES PATENT OFFICE

139,402

DESIGN FOR A CLINOMETER

John L. Chaney, Lake Geneva, Wis.

Application March 23, 1944, Serial No. 113,012

Term of patent 14 years

(Cl. D52—1)

To all whom it may concern:

Be it known that I, John L. Chaney, a citizen of the United States of America, residing at Lake Geneva, in the county of Walworth, State of Wisconsin, have invented a new, original, and ornamental Design for Clinometer, of which the following is a specification, reference being had to the accompanying drawing, forming a part thereof in which,

Fig. 1 is a view in front elevation of a clinometer showing my new design; and

Fig. 2 is a view in side elevation thereof.

The indicia for reading the position of the marker as shown in the drawing are merely illustrative.

I claim:

The ornamental design for a clinometer, substantially as shown and described.

JOHN L. CHANEY.
